UNITED STATES PATENT OFFICE.

IRWIN A. SEIDERS, OF READING, PENNSYLVANIA.

METAL CAR END.

Application filed February 18, 1922. Serial No. 537,361.

To all whom it may concern:

Be it known that I, IRWIN A. SEIDERS, a citizen of the United States, residing at Pennside, Reading, in the county of Berks 5 and State of Pennsylvania, have invented a certain new and useful Improvement in Metal Car Ends, of which the following is a full, clear, concise, and exact description, reference being had to the accompanying 10 drawings, forming a part of this specification.

This invention relates to improvements in metal car ends.

One object of the invention is to provide 15 an efficient, durable and economical metal end for cars, and more especially box cars.

A more specific object of the invention is to provide a sheet metal end having great strength against endwise thrusts to prevent 20 bulging, and which also affords great strength against vertical and horizontal forces which may be exerted on the end so that the metal end effectively serves to rigidify the car superstructure to prevent 25 skewing or weaving.

In the drawings forming a part of this specification, Figure 1 is an elevational view of the end of a box car showing my improvements applied thereto. Figure 2 is a 30 horizontal sectional view corresponding to the section line 2—2 of Figure 1. Figure 3 is a vertical, sectional view corresponding to the section line 3—3 of Figure 1. Figure 4 is a side elevational view of the sheet 35 metal end, detached. Figures 5 and 6 are sectional views corresponding to the section lines 5—5 and 6—6 respectively of Figure 1.

In said drawings, the car roof is indicated 40 at 10, the side walls at 11, the corner posts at 12, the end plate at 13, end fascia board at 14, center sills at 15, side sills at 16, floor at 17, buffer block or casting at 18, and end sill at 19.

45 The improved sheet metal end proper, as shown, comprises, preferably, an upper section or half A and a lower section or half B.

The upper section A is provided with a 50 series of integrally formed strengthening indentations in the form of corrugations designated at 20, 21, 22, 23, 24, 25, 26, 27 and 28. The corrugations 20 to 24 inclusive consist each of two portions intersecting in the vertical central line of the end and 55 diverging downwardly therefrom, the corrugation 20 obviously being the shortest and

the others progressively greater in extent until the maximum is reached at 24. In each upper outer corner of the top half or section A of the end wall, are the other corrugations 25, 26, 27 and 28, parallelly arranged and progressively decreasing in length as they approach the corner, as clearly seen in Figure 1. All of said corrugations 20 to 24 inclusive have their lower ends terminated in substantially a horizontal line, as clearly shown in Figure 1.

The bottom half or section B of the car end is provided with a similar series of but oppositely arranged integral corrugations 70 20^a, 21^a, 22^a, 23^a, 24^a, 25^a, 26^a, 27^a, and 28^a. All of said corrugations 20^a to 24^a inclusive have their upper ends terminated in substantially a horizontal line, the ends of the corrugations 20 and 20^a; and 21 and 21^a, etc., 75 being disposed vertically opposite each other.

From the preceding description, considered in connection with the drawing, and assuming the end wall as an entirety divided 80 into four quarter sections, it will be found that the corrugations in each quarter section are approximately perpendicular to a diagonal of the end wall passing therethrough and furthermore that the various 85 sets of corrugations 20 and 20^a, 21 and 21^a, etc., form, in effect, diamond shaped corrugations of graduated extent outwardly from the center of the end wall toward the edges and top, except for the omissions which 90 occur where the sheets of the upper and lower halves of the end wall are overlapped.

With the arrangement of corrugations shown, not only do I obtain great strength 95 against endwise thrusts occurring in service due to shifting of the load or pressure from loads of a more or less fluid character, but I also greatly strengthen the end wall against any tendency to collapse or skew from forces applied thereto from either side or 100 from the top or from the bottom. In other words, the sheet metal end, when secured to the side wall, roof and floor structure of the car, affords great strength to the 105 superstructure in resisting tendency of the superstructure to weave or skew in directions transversely of the car.

The two sections A and B of the end wall are overlapped as indicated at a—b best in Figure 3 and secured by a horizontally extending series of rivets 29. To secure the 110 car end along its vertical sides, the car end

is left with right angled flanges 30—30 lapping around the corner posts 12 and secured thereto in any desired manner. At the top, the horizontal upper edge of the 5 panel or section A is bolted to the end plate 13, as shown in Figures 1 and 3, the end plate being preferably rabbeted so as to leave the outer face of the sheet metal flush with the outer surface of the end plate 13. 10 At the bottom, the lower panel B has its lower edge extended inwardly horizontally as indicated at 31, the end sill 19 being applied thereover. Preferably a short section of angle 32 is used on the outer side of the 15 end wall opposite the buffer casting 18, said angle section 32 and inner angle iron 19 being riveted together through the sheet metal end wall.

Owing to the side flanges 30 of the two 20 panels A and B, where they are overlapped, I preferably offset outwardly the flange 30 of the top panel A as indicated at 30^a in Figure 4 and the lower edge of the panel A near the side is also preferably offset as 25 indicated at 30^b, the latter offset however gradually merging into the lap joint as shown in Figure 3.

I have herein shown and described what 30 I now consider the preferred manner of carrying out the invention but the same is merely illustrative and I contemplate all changes and modifications that come within the scope of the claims appended hereto.

I claim:

35 1. A sheet metal car end having strengthening indentations therein, all extending substantially parallel to diagonal lines of the end, all the indentations in any one quarter section of the end being approximately at right angles to all of the indentations in an adjacent quarter section.

40 2. A sheet metal car end having strengthening indentations therein, all extending substantially parallel to diagonal lines of the end, the indentations in any two adjacent quarter sections of the end being approximately at right angles to each other, said end comprising upper and lower panels rigidly united.

45 3. A sheet metal car end having integrally formed corrugations therein, said corrugations, in each quarter section of the end, be-

ing all parallel and all extending transverse to a diagonal line of the end passing through said quarter section. 55

4. A sheet metal car end having integrally formed corrugations therein, said corrugations, in each quarter section of the end, being all parallel and all extending transverse to a diagonal line of the end passing 60 through said quarter section, said end comprising upper and lower panels rigidly united by a horizontally extending lap joint.

5. A sheet metal car end having in the upper portion thereof, a plurality of intersecting corrugations all diverging downwardly from a vertical centrally disposed line to substantially a common horizontal line and, in the lower portion thereof, having a plurality of corrugations all diverging upwardly from said vertical line to a substantially common horizontal line. 65

6. A sheet metal car end having in the upper portion thereof, a plurality of intersecting corrugations diverging downwardly 75 from a vertical centrally disposed line and in the lower portion thereof, having a plurality of intersecting corrugations diverging upwardly from said line, the lower ends of said first named corrugations terminating 80 opposite the respective upper ends of the second named corrugations, said end being formed of two panels rigidly united by a horizontally extending lap joint.

7. A sheet metal car end comprised of an 85 upper panel and a lower panel united by a horizontally extending lap joint, said upper panel having integrally formed therein, a series of intersecting corrugations diverging 90 downwardly from a central vertically extended line and all terminating in a substantially common horizontal line and additional corrugations in the upper corners of the panel, said lower panel having similarly arranged corrugations but extended in the 95 opposite direction.

In witness that I claim the foregoing I have hereunto subscribed my name this 31st day of January, 1922.

IRWIN A. SEIDERS.
